US00D831565S

(12) **United States Design Patent** (10) Patent No.: **US D831,565 S**
(45) Date of Patent: **** Oct. 23, 2018**

(54) AC/DC ADAPTER WITH MOUNT	4,309,096 A	1/1982	Sethi
(71) Applicant: GOOGLE LLC , Mountain View, CA (US)	D268,672 S	4/1983	McPherson
(72) Inventors: Adam Duckworth Mittleman , Redwood City, CA (US); Jason Evans Goulden , Los Gatos, CA (US); Nicholas Webb , Menlo Park, CA (US); Gregory Daniel Louis Germe , Oakland, CA (US); William Raeming Dong , Palo Alto, CA (US); Rochus Jacob , San Francisco, CA (US)	4,439,643 A	3/1984	Schweizer
	D296,013 S	5/1988	Layne et al.
	5,039,366 A	8/1991	Strattman
	1,934,911 A	11/1993	Campbell
	D349,714 S	8/1994	Hasegawa
	D353,904 S	12/1994	Swanson
	5,439,387 A	8/1995	Hayashi
	5,441,224 A	8/1995	Ludwig
	5,482,234 A	1/1996	Lyon
	D390,482 S	2/1998	Pasquarette
	D399,584 S	10/1998	Giese et al.
	6,007,136 A	12/1999	Zittwitz
	D427,696 S	7/2000	Scott et al.
	D431,307 S	9/2000	Zelina, Jr. et al.
	D433,994 S	11/2000	Jobs et al.
	6,176,142 B1	1/2001	Ericson
	6,196,915 B1	3/2001	Schiedegger et al.
	D440,330 S	4/2001	Scott et al.
	6,234,277 B1	5/2001	Kaczmarek
	6,644,617 B2	11/2003	Pitlor
	6,732,983 B1	5/2004	Blake et al.
	D506,565 S *	6/2005	Yurich D26/85
	D509,842 S	9/2005	Ou
	D528,576 S	9/2006	Chung et al.
	7,162,790 B1	1/2007	Daniels
	D537,784 S	3/2007	Suckle et al.
	D553,659 S	10/2007	Kweon
	D554,171 S	10/2007	Deng
	D593,071 S	5/2009	Laituri et al.
	7,641,161 B2	1/2010	Bauer
	D623,594 S	9/2010	Akana et al.
	D640,721 S	6/2011	Satine
	D644,259 S	8/2011	Barley et al.
	D659,282 S	5/2012	Richmond
	D659,497 S	5/2012	Blazevic
	D662,122 S	6/2012	Goodwin et al.
	D670,426 S	11/2012	Bouroullec et al.
	D691,587 S	10/2013	Ferber et al.
	D697,481 S	1/2014	Akana et al.
	D700,075 S *	2/2014	Bould D10/49
	D708,378 S	6/2014	Recker et al.
	D720,755 S	1/2015	Nokuo
	D729,773 S *	5/2015	Salojarvi D14/218
	9,024,581 B2	5/2015	McGinley
	D737,762 S *	9/2015	Aumiller D13/108
	D742,573 S	11/2015	Kern et al.
	D742,884 S	11/2015	Seflic et al.
	D743,468 S	11/2015	Ribeiro et al.
	D743,954 S *	11/2015	Chuang D13/168
	9,190,767 B2	11/2015	Makimura
	D747,524 S	1/2016	Jacq et al.

D784,263 S	4/2017	Xu		(57) CLAIM
D785,632 S	5/2017	VanDuyne et al.		An AC/DC adapter with mount, as shown and described.
D785,693 S	5/2017	Kim		DESCRIPTION
D786,875 S	5/2017	Kaminaga		FIG. 1 is a first perspective view of our new design of an AC/DC adapter with mount;
D788,112 S	5/2017	Liao		FIG. 2 is a second perspective view thereof;
D788,708 S	6/2017	Vo et al.		FIG. 3 is a top view thereof;
D788,777 S	6/2017	Bargetzi		FIG. 4 is a bottom view thereof;
D789,371 S	6/2017	Iwamoto et al.		FIG. 5 is a first side view thereof; and,
D790,620 S	6/2017	Lee et al.		FIG. 6 is a second side view thereof.
D791,740 S	7/2017	Fuller		The broken lines in the above described FIGS. 1-6 depict environmental matter and form no part of the claimed design.
D794,028 S	8/2017	Lin		
D795,941 S	8/2017	Dimitriadi et al.		
D796,513 S	9/2017	Feldstein et al.
